EXCAVATING APPARATUS

Filed Jan. 30, 1928

Inventor:
John F. Page,
B. F. C. & Co.,
Attns.

UNITED STATES PATENT OFFICE.

JOHN W. PAGE, OF CHICAGO, ILLINOIS.

EXCAVATING APPARATUS.

Application filed January 30, 1928. Serial No. 250,447.

This invention relates to improvements in excavating apparatus, and more especially such apparatus adapted for digging trenches and sometimes referred to as a 5 trench hoe. My improved apparatus will be fully disclosed in the following specification and accompanying drawings.

In that form of device embodying the features of my invention shown in the 10 drawings, Figure 1 is a view in side elevation, Fig. 2 is a fragmentary view on an enlarged scale, of the pivot connection of the boom, Fig. 3 is a view of the boom in front elevation, Fig. 4 is a view in side elevation showing the connection between the boom and the bucket-arm, and Fig. 5 is a view of the bucket in front elevation.

As shown in the drawings, 10 indicates a suitable platform of the ordinary type rotatably mounted by means of the turntable 11 on suitable traction members, for example the caterpillar track 12. The platform 10 is adapted to support the driving machinery (not shown) which may be any suitable 25 motor. 13 indicates a suitable housing for the mechanism mounted on the platform 10, and the operator.

Pivottally attached at 14 to the front of the platform 10 in the usual manner is a 30 boom 15. 16, 16 indicate suitable stay members.

17 indicates a bucket-arm pivotally attached to the end of the boom 15 at 18, such point of attachment being a short distance 35 below the upper end of the arm 17. The lower end of the arm 17 is forked as indicated by 17^a, the prongs of the forks carrying pivotally mounted therebetween a bucket 19 which may be the general type of Page 40 bucket now in common use in excavating apparatus. The pivot points at which the bucket 19 is carried by the end of the arm are indicated by 20, 20 and these pivot points preferably are in front of the center of 45 gravity of the bucket.

21 indicates an A-frame mounted on the platform 10 with a double sheave 22 at its apex. The upper end of the arm 17 is also provided with a double sheave 23. The 50 bucket 19 is provided with a rearwardly extending arm 24, the end of said arm as indicated by 24^a lying behind the pivot point 20 and preferably behind the center of gravity of the bucket.

55 25 indicates a boom line having one end

attached to the winch or winding drum 25^a on the platform 10. This line 25 extends from the winding drum 25^a up over one of the sheaves at the top of the A-frame, thence around one of the sheaves 23 at the upper 60 end of the arm 17, thence back around the other sheave 22, thence over the other sheave 23 and downwardly parallel with the arm 17 where its other end is attached at 24^a to the arm 24 on the bucket.

26 indicates a loading-line attached to the front of the shovel 26^a, preferably by means of a bridle chain 26^b. The other end of the loading-line 26 passes over the roller 27 and under the roller 28 and thence is 70 led to the winch or winding drum 29 mounted on the platform 10.

The operation is as follows. With the arm and boom pretty well extended the end of the arm is permitted to drop. The loading-line is left somewhat slack so that the bucket descends cutting-edge first. The bucket is then hauled in by the loading-line and the loading is greatly facilitated because most of the weight of the boom and arm is concentrated at a point almost directly over the cutting-edge. After the bucket has been filled, tension is maintained on the loading-line and the boom-line is hauled in to move the bucket upwardly and outwardly. By 75 maintaining tension on the loading-line the bucket remains in horizontal position thus preventing the load from being dumped. As the arm approaches a horizontal position, however, as shown by the broken lines in 80 Fig. 1, the strain on the boom-line 25 increases thus pulling harder on the arm 24 and tending to dump the bucket. The exact time at which the bucket is to be dumped may be determined by the operator. He may 85 haul in on the boom-line until there is sufficient tension on the same to overcome the tension on the loading-line; or, he may cause the bucket to dump somewhat sooner by slackening away slightly on the loading-line. 90 In other words, the boom-line tends to hold it in horizontal or load-retaining position. The operator may control these two lines to cause the dumping to occur when he wishes. It will be seen, however, that the manipulation is rather simple because when the bucket 95 has been filled and the arm is almost in vertical position but slight tension on the loading-line will overcome the pull on the boom-line and maintain the bucket in load-retain-

112

ing position. As the bucket is raised and moved outwardly by hauling in the boom-line the tension on the boom-line continues to increase. That is, as the arm 17 gets 5 higher and approaches the horizontal position the tension on the boom-line 25 increases until finally the normal tension on the loading-line will automatically be overcome thus causing the bucket to dump without any particular manipulation by the operator.

My improved excavating apparatus is a great improvement over the ordinary type of trench hoe now in common use in which 15 the bucket is rigidly mounted on the arm. In such devices, as the arm goes backwards the load commences to spill as soon as the bucket begins to move out of its horizontal position. Also, my improved excavating device is adapted to dig to a greater depth than 20 those of the old type just mentioned.

While I have shown and described certain embodiments of my invention, it is to be understood that it is capable of many modifications. Changes, therefore, in the construction and arrangement may be made without departing from the spirit and scope of the invention disclosed in the appended claims, in which it is my intention to claim all 30 novelty in my invention as broadly as possible in view of the prior art.

What I claim is new, and desire to secure by Letters Patent, is:

1. Excavating apparatus comprising; a 35 platform; a boom pivotally attached to the platform; a bucket-arm pivotally attached to the outer end of the boom, said pivotal attachment being below the upper end of said bucket-arm; a bucket pivotally mounted on the lower end of the bucket-arm, and adapted to rotate on said pivot from horizontal load-retaining position to vertical dumping position; a loading-line attached to the bucket in front of its pivotal attachment to the bucket-arm, whereby tension on said loading-line tends to hold said bucket in horizontal load-retaining position; means on the platform for hauling in the loading-line; a boom-line leading from the platform 40 to the upper end of the bucket-arm and thence to the bucket, the end of said boom-line being attached to said bucket behind the pivotal attachment between said bucket and the bucket-arm, whereby tension on said boom-line tends to rotate the bucket to vertical dumping position; and means on the platform for hauling in the boom-line.

2. Excavating apparatus comprising; a 45 platform; a boom pivotally attached to the platform; a bucket-arm pivotally attached to the outer end of the boom, said pivotal attachment being below the upper end of said bucket-arm; a bucket pivotally mounted on the lower end of the bucket-arm and adapted to rotate on said pivot from hori-

zontal load-retaining position to vertical dumping position; a loading-line attached to the bucket; means on the platform for hauling in the loading-line; a boom-line leading from the platform to the upper end of the bucket-arm and thence to the bucket; means on the platform for hauling in the boom-line; and means for rotating the bucket on its pivotal attachment to the bucket-arm from horizontal load-retaining position 70 to vertical dumping position, said means being operated by tension on the boom-line.

3. Excavating apparatus comprising; a platform; a boom pivotally attached to the platform; a bucket-arm pivotally attached to the outer end of the boom, said pivotal attachment being below the upper end of said bucket-arm; a bucket pivotally mounted on the lower end of the bucket-arm and adapted to rotate on said pivot from horizontal load-retaining position to vertical dumping position; a loading-line attached to the bucket, tension on said loading-line tending to hold said bucket in horizontal load-retaining position; means on the platform for hauling in the loading-line; a boom-line leading from the platform to the upper end of the bucket-arm and thence to the bucket; means on the platform for hauling in the boom-line; and means for rotating the bucket on its pivotal attachment to the bucket-arm from horizontal load-retaining position 80 to vertical dumping position, said means being operated by tension on the boom-line.

4. Excavating apparatus comprising; a platform; a boom pivotally attached to the platform; a bucket-arm pivotally attached to the outer end of the boom; a bucket pivotally mounted on the lower end of the bucket-arm, and free to rotate on said pivot from horizontal load-retaining position to vertical dumping position except as held by tension on the loading line; a loading-line attached to the bucket, tension on said loading-line tending to hold said bucket in horizontal load-retaining position; means on the platform for hauling in the loading-line; means for lifting the lower end of the bucket-arm with the bucket; and means for rotating the bucket on its pivotal attachment to the bucket-arm from horizontal load-retaining position 90 to vertical dumping position.

5. Excavating apparatus comprising; a 100 platform; a boom pivotally attached to the platform; a bucket-arm pivotally attached to the outer end of the boom; a bucket pivotally mounted on the lower end of the bucket-arm and adapted to rotate on said pivot from horizontal load-retaining position to vertical dumping position; a loading-line attached to the bucket; means on the platform for hauling in the loading-line; a line 105 for lifting the lower end of the bucket-arm 110 to vertical dumping position.

with the bucket, said line having its outer end attached to the bucket; and means for rotating the bucket on its pivotal attachment to the bucket-arm from horizontal load-retaining position to vertical dumping position, said means operated by tension on the line for lifting the lower end of the bucket-arm. 5

6. Excavating apparatus comprising; a platform; a boom pivotally attached to the platform; a bucket-arm pivotally attached to the outer end of the boom; a bucket pivotally mounted on the lower end of the bucket-arm and adapted to rotate on said pivot from horizontal load-retaining position to vertical dumping position; a loading-line attached to the bucket, tension on said loading-line tending to hold the bucket in horizontal load-retaining position; means on the platform for hauling in the loading-line; a line for lifting the lower end of the bucket-arm with the bucket, said line having its outer end attached to the bucket; and means for rotating the bucket on its pivotal attachment to the bucket-arm from horizontal loading-retaining position to vertical dumping position, said means operated by tension on the line for lifting the lower end of the bucket-arm. 10 15 20 25

7. In combination with suitable winding machinery, a trunnioned boom, a bucket arm rotating about a point in the boom, a bucket

trunnioned on the bucket arm, a loading line attached to the bucket and adapted to rotate and maintain the bucket in a load-carrying position, and a boom line having one end attached to the bucket and adapted to raise and lower the boom and to rotate and maintain the bucket in a dumping position. 35 40

8. Excavating apparatus comprising; a platform; a boom pivotally attached to the platform; a bucket-arm pivotally attached to the outer end of the boom; a bucket pivotally mounted on the lower end of the bucket-arm; a loading line attached to the bucket, tension on said loading line tending to hold said bucket in horizontal load-retaining position, said bucket being free to rotate on its pivot from horizontal load-retaining position to vertical dumping position, except as held by tension on said loading line; means on the platform for hauling in the loading line; means for lifting the lower end of the bucket-arm with the bucket, said means including a line having one end attached to the bucket, tension on said line tending to rotate said bucket on its pivotal attachment to vertical dumping position; and means on the platform for hauling in said last-mentioned line. 45 50 55 60

In witness whereof, I have hereunto set my hand this 27th day of January, 1928.

JOHN W. PAGE.
